Primary Examiner — Darlington Ly

(57) **CLAIM**

The ornamental design for a tire tread, as shown and described.

DESCRIPTION

1. Tire tread

1.1 is a perspective view of a tire tread showing my new design;

1.2 is a front elevation view thereof;

1.3 is a left side elevation view thereof;

1.4 is a rear elevation view thereof;

1.5 is a right side elevation view thereof;

1.6 is an enlarged and partial front elevation view thereof;

1.7 is a cross-sectional view thereof taken along line 7-7 in 1.6;

1.8 is a cross-sectional view thereof taken along line 8-8 in 1.6; and

1.9 is a cross-sectional view thereof taken along line 9-9 in 1.6.

The broken line showings of the tire sidewalls are provided for the purpose of illustrating environmental structure and form no part of the claimed design.
